WINDING AND TWISTING

Robert H. Legard, Jr., Narrows, and Earl R. Meadows, Pearisburg, Va., assignors to Celanese Corporation of America, New York, N. Y., a corporation of Delaware

Application September 24, 1954, Serial No. 458,076

1 Claim. (Cl. 57—93)

This invention relates to winding and twisting and relates more particularly to apparatus for winding and twisting filamentary material to form a package of filamentary material having substantially uniform twist throughout its length.

It is an object of this invention to provide novel winding and twisting apparatus in which filamentary material is wound into a package and twisted in such a manner that the degree of twist is substantially uniform throughout said package.

Other objects of this invention, together with certain details of construction and combinations of parts, will be apparent from the following detailed description and claim.

In the accompanying drawing wherein a preferred embodiment of this invention is shown:

Fig. 1 is a view in perspective of the general arrangement of the apparatus; and

Fig. 2 is a view in perspective of the speed-varying mechanism employed in the apparatus of this invention.

Like reference numerals refer to like parts throughout both views of the drawing.

Referring now to the drawing, and in particular to Fig. 1 thereof, reference numeral 11 designates a supply bobbin wound with yarn 12 to be twisted. While two supply bobbins are shown in the drawing, the descriptions will be limited to one since both bobbins are operated by similar elements. The bobbin 11 is mounted on and rotated by a rotatable vertical spindle 13 which is driven by the engagement of a travelling belt 14 with a whorl 16 formed on said spindle, the belt 14 being in turn driven by a motor 17 through a driving pulley 18. The yarn is drawn off the end of the bobbin 11 through a fixed guide 19 positioned at a point above the spindle 13 and then passes over a plate 21 and through a ceramic button guide 22, movably supported on said plate 21, to a driven yarn package support, such as a conical or cylindrical tube, on which it is taken up in the form of a yarn package 23. The button guide 22 is moved by any suitable traversing mechanism to and fro along the length of the yarn package 23 in order to form said package in the desired winding pattern.

During its passage between the revolving supply bobbin 11 and the button guide 22 the yarn 12 becomes twisted, the extent of the twist, as measured in turns per inch, depending completely on the relation between the rotational speed of the driven supply bobbin 11 and the linear speed of the yarn 12. The linear speed of the yarn itself is a function of the rotational speed of the yarn package 23 and the diameter of said yarn package at the point where the yarn is being wound. Accordingly, if the package 23 were rotated at a constant rotational speed the linear speed of the yarn 12 would increase as the yarn built up on the package. If at the same time the rotational speed of the bobbin 11 were kept constant, the degree of twist on the yarn, as measured in turns per inch, would decrease as the winding of the yarn on the cone progressed.

The apparatus of this invention includes an arrange-

2

ment for decreasing the rate of rotation of the package 23 as the winding of the yarn 12 thereon proceeds. More particularly, the package 23 is driven through a belt 24, engaging a pulley 26 on a shaft 27 on which the cone is mounted; the belt 24 being driven through a positive infinitely variable transmission, generally indicated by reference numeral 28, having parallel input and output shafts 31 and 32, respectively. The output shaft 32 serves to drive the belt 24 while the input shaft 31 is rotated either by the motor 17 which drives bobbin 11 or by any other suitable prime mover whose speed is maintained at a value which bears a constant ratio to the speed of said bobbin 11.

The positive infinitely variable transmission 28 comprises (Fig. 2) a pair of pulleys 33 having opposed generally conical grooved faces 34 and mounted on the output shaft 32 and a pair of similar pulleys 36 mounted on the input shaft 31. The shafts 31 and 32 are splined as at 37 so that the pulleys of each pair can be moved closer together or farther apart. The shafts 31 and 32 are kinematically connected, through the pulleys 33 and 36, by an endless belt 38 having toothed edges 39, with the teeth of the belt 38 engaging in the grooves of the conical faces 34 of the pulleys 33 and 36. It will be apparent that if pulleys 33 are moved axially closer together while the pulleys 36 are moved axially further apart the toothed belt 38 will engage the pulleys 36 at a point closer to the axis of the input shaft 31 and will engage the pulleys 33 at a point farther from the axis of the output shaft 32, thereby decreasing the ratio between the speed of the output shaft and the speed of the input shaft. These axial movements of the pulleys 33 and 36 are effected by means of levers 41, 42 mounted along the sides of said pulleys. Each lever 41, 42 is in the form of a pair of members 43, 44, one below and one above the shafts 31 and 32, said members 43, 44 being connected by pins 46. Each lever is pivoted on a vertical axis 47 between the shafts 31 and 32 and is connected to pulleys 33 and 36 at opposite sides of said pivotal axis 47.

The positions of the levers 41, 42 are controlled by a pair of aligned rods 48, 49, respectively. One end of each rod is connected to the end of one of the levers by pins 51, 52, while the opposite end (Fig. 1) of each rod 48, 49 abuts against the surface of one of a pair of rotary cams 53, 54. The rods 48, 49 are urged apart and pressed against the cams 53, 54, respectively, by a spring 56 (Fig. 2) mounted between the pins 51, 52. The cams 53, 54 are driven at equal speeds, through an arrangement of shafts, pulleys and gearing, which arrangement is designated generally by reference numeral 57, by the motor 17, the arrangement being such that each cam 53, 54 makes one complete revolution during the period of time necessary to wind the package 23 fully. It will be appreciated, of course, that the cams 53, 54 may be driven by any other prime mover whose speed is constantly proportional to that of the motor 17. For example, when the speed of the motor 17 is constant the cams may be driven by any suitable timing arrangement.

The constructions of the cams 53, 54 and their directions of rotation are such that the rods 48, 49 are forced most closely towards each other by said cams at the beginning of the winding of the package 23. As the winding progresses the cams permit the rods 48, 49 to spread further apart in response to the urging of the spring 56, and thus cause the rotational speed of the package 23, relative to the speed of the bobbin 11, to decrease until the package 23 has been fully wound, at which time the cams have completed one cycle of revolution and the rods 48, 49 are again forced closely together by said cams and the fully wound yarn package 23 is replaced by an empty yarn package support, e. g. a conical or cylindrical tube. The replacement of the fully wound yarn package by an empty

yarn package support is effected by the operator of the machine or by any suitable automatic arrangement.

As indicated in the drawing and mentioned above the device of this invention will generally contain a plurality of spindles 13, all driven at the same speed from a common motor 17, and a plurality of packages 23, which may be conical or cylindrical or both, all driven at the same speed from the output shaft 32. In this case all the yarn packages should be doffed and donned at the same time. During the period when all the packages are doffed and donned the rotation of the cams 53, 54 should be stopped in order to insure that the cams will be at the proper point when winding begins again.

It is to be understood that the foregoing detailed description is merely given by way of illustration and that many variations may be made therein without departing from the spirit of our invention.

Having described our invention, what we desire to secure by Letters Patent is:

Apparatus for the twisting and winding of filamentary material comprising a spindle for holding and rotating a wound package of filamentary material, means for driving said spindle, a mounting for holding and rotating a support for a second package of filamentary material to wind the filamentary material from said first package onto said second package, means for driving said mounting, a guide positioned axially of said spindle for receiving the filamentary material being unwound from said first package, the construction and arrangement being such that said yarn becomes twisted as it passes from said first package to said second package, means for varying the relative speeds of said two driving means so as to decrease the speed of said mounting driving means relative to the speed of said spindle driving means as the diameter of said second package increases due to the winding of fila-

mentary material thereon, said varying means comprising an input shaft driven at a speed proportional to the speed of said spindle and carrying a pair of pulleys having opposed conical faces, an output shaft connected to said mounting driving means and carrying a pair of pulleys having opposed conical faces, an endless belt connecting said pairs of pulleys and engaging said conical faces for driving said output shaft thereby, a pair of levers, each of said levers being operatively connected to one of each of said pairs of pulleys for varying the spacing of said pulleys so as to vary the ratio of the speeds of said input and output shafts, a spring acting on said levers and urging said levers in a direction to increase the ratio of the speeds of said input and output shafts, a pair of rods each connected to one of said levers, a pair of rotatable cams having surfaces engaged by said rods for operating said levers through said rods, the surfaces of said cams being so constructed as to effect, by their operation of said levers, an increase in the ratio of the speeds of said input and output shafts during the time necessary to wind said second package fully, and means for driving said cams at a speed proportional to the speed of said spindle and at a rate such that the desired increase in the ratio of the speeds of said input and output shafts is effected during each cycle of complete winding of said second package.
